(57) **CLAIM**

The ornamental design for a cane tip, as shown and described.

DESCRIPTION

FIG. 1 is a front perspective view of a cane tip shown with an environment. The broken line showing of the lower portion of a cane is included for the purpose of illustrating an environment that forms no part of the claimed design.

FIG. 2 is a front elevational view thereof.

FIG. 3 is a rear elevational view thereof.

FIG. 4 is a left side elevational view thereof, with the right side elevational view being a mirror image of FIG. 4.

FIG. 5 is a top view thereof; and,

FIG. 6 is a bottom view thereof.
